Primary Examiner—Dominic Simone
Attorney, Agent, or Firm—Fish & Richardson P.C.[57] **CLAIM**

The ornamental design for a shoe upper element, as shown and described.

DESCRIPTION

FIG. 1 is a bottom plan view of a shoe upper element showing my new design;

FIG. 2 is a right side view thereof;

FIG. 3 is a left side view thereof;

FIG. 4 is a front view thereof;

FIG. 5 is a top view thereof;

FIG. 6 is a rear view thereof;

FIG. 7 is a cross-sectional view thereof taken along the line 7—7 of FIG. 3;

FIG. 8 is a cross-sectional view thereof taken along the line 8—8 of FIG. 3;

FIG. 9 is a cross-sectional view thereof taken along the line 9—9 of FIG. 3;

FIG. 10 is a bottom plan view of a second embodiment of a shoe upper element according to my new design;

FIG. 11 is a right side view of the second embodiment;

FIG. 12 is a left side view of the second embodiment;

FIG. 13 is a front view of the second embodiment;

FIG. 14 is a rear view of the second embodiment; and,

FIG. 15 is a top view of the second embodiment.

The dotted line showing of a shoe sole in FIGS. 2 and 11 is for illustrative purposes only and forms no part of the claimed design.
